UNITED STATES PATENT OFFICE.

ALDEN L. PUTNAM, OF DETROIT, MICHIGAN, ASSIGNOR, BY MESNE ASSIGNMENTS, TO DETROIT PRESSED STEEL COMPANY, OF WILMINGTON, DELAWARE, A CORPORATION OF DELAWARE.

REVERSIBLE DISK WHEEL.

Application filed September 28, 1918. Serial No. 256,009.

To all whom it may concern:

Be it known that I, ALDEN L. PUTNAM, a citizen of the United States of America, residing at Detroit, in the county of Wayne 5 and State of Michigan, have invented certain new and useful Improvements in Reversible Disk Wheels, of which the following is a specification, reference being had therein to the accompanying drawings.

10 The invention relates to vehicle wheels of the dished disk type. In the present state of the art it is usual to secure the disk to the hub with the dish on the outer side. The tire-holding rim is secured to the periphery of 15 the disk but instead of the point of attachment being at the center of the rim it is forward of the center so that the body of the disk crosses the central plane of impact. Such a construction has various advantages 20 but there is the disadvantage of locating the tire inflation tube back of the disk, where it is not as readily accessible. Therefore, for certain uses the outward dishing of the disk is not as desirable as the reverse 25 arrangement or inner dishing. It is not, however, possible to reverse the disk in this engagement with the hub for the reason that this would change the tread of the wheel to a different distance from the center of 30 the vehicle.

It is the object of the present invention to provide a construction of disked wheel which is reversible so that the advantages of the outward dishing may be utilized whenever possible, but for certain uses they may be dispensed with to secure the advantages of the inner dishing. It is also an object to permit of thus reversing the disk without any change in the tread of the wheel, and 35 still further to provide for the mounting of such reversible disks on hubs designed for use with non-reversible disks. The invention therefore comprises the novel features of construction as hereinafter set forth.

40 In the drawings:

Figure 1 is a vertical central section through a wheel of my improved construction;

Figure 2 is a similar view showing the 45 disk in reverse position;

Figure 3 is a similar view of a modified construction of hub.

A is the disk, B the hub on which the disk

is detachably mounted, C is the tire-holding 55 rim secured to the periphery of the disk, and D is the brake-drum. As heretofore constructed the disk is detachably secured to the hub by a flange F on the latter and studs G projecting therefrom engaging 60 apertures in the disk and clamped by nuts H. The dish is arranged outward and the flange F on the hub is upon the opposite 65 side of the central plane of impact from the peripheral portion of the disk where it is attached to the rim. With my improved 70 construction I may, if desired, use the same construction of hub with the same location of the flange F, but in that case an annular member I is provided and arranged to lie adjacent to the flange F so as to bring the 75 bearing face for the disk substantially at the center of the wheel or in the plane of impact. The studs G serve to clamp the member I in position and the brake-drum D may be secured by clamping its inwardly 80 extending flange D' between the flange F and the member I. The construction of the disk A is also such that its inner portion which fits about the hub and lies adjacent to the member I will be arranged substantially in the plane of impact.

With the modifications in construction just described the wheel is adapted to be mounted alternatively in reverse position without changing the line of tread. Thus, as shown 85 in Figure 1, the dish is outward, meaning by this that the periphery of the disk is outward from the plane of impact. If, however, it is desired to mount the wheel in reverse position so as to provide more ready 90 access to the tire tube or for any other purpose, the disk may be removed and reversed without changing the line of tread, this arrangement being shown in Figure 2.

Where the hub is built to be used exclusively with the type of wheel above described, instead of arranging the flange F inside of the plane of impact it may be arranged as shown in Figure 3, in which F' is a flange having its outer face adjacent to 100 the plane of impact and against which the disk is directly clamped. The brake-drum is secured upon the opposite side of this flange and a detachable ring J is engaged with the studs on the disk side, being 105 clamped in position by the nuts H. To

change the position of the wheel it is only necessary to remove the nuts H, detach and reverse the disk and re-clamp the same.

What I claim as my invention is:—

- 5 1. The combination of a wheel hub having an outwardly extending flange adjacent to the central plane of impact and a demountable wheel comprising a dished disk, the central portion of said disk being also arranged in the central plane of impact, and means for clamping said disk to said flange alternatively in reverse positions.
- 10 2. The combination with a wheel hub having a flange extending from the periphery thereof, of a demountable wheel comprising a dished disk, the central portion of said disk being arranged adjacent to the central plane of impact of the wheel, and co-operating studs and clamping nuts for engaging and securing said disk in reverse positions upon said hub.
- 15 3. The combination with a wheel hub having a flange extending from the periphery, of a demountable wheel comprising a dished disk and a tire-engaging rim secured to the periphery thereof, the proportions being such that the rim will be located the same in reverse positions on said wheel and with the disk adjacent to said flange, and clamping

means for securing said disk to said flange in either of its reverse positions.

4. The combination with a wheel hub, of a brake-drum and a demountable wheel having a dished disk and tire-engaging rim, a bearing secured to said hub having said disk arranged on one side thereof and said brake-drum on the opposite side, and means for clamping said disk to said bearing in either one of its reverse positions.

5. A demountable wheel, comprising a tire-engaging rim and a dished disk having its peripheral portion opposite to said rim on one side of the plane of impact, the center portion of the disk being arranged substantially in the plane of impact, and means for clamping said disk to said hub alternatively in reverse positions.

6. In combination with a hub provided with a flange substantially offset from the plane of the center of the tread of the wheel, a disk wheel adapted to seat upon the hub and reversible, a spacer between the wheel and the hub flange to allow the wheel to be reversed without changing the wheel gauge, and means for securing the wheel upon the hub.

In testimony whereof I affix my signature.
ALDEN L. PUTNAM.
